COOLER OF DISCHARGE TUBES

Florus Cornelis Willem Slooff, Eindhoven, Netherlands, assignor to Hartford National Bank and Trust Company, Hartford, Conn., as trustee

Application May 7, 1948, Serial No. 25,672
In the Netherlands June 18, 1947

3 Claims. (Cl. 250—27.5)

1

This invention relates to electric discharge tubes and more particularly to the cooling of high power discharge devices and a supporting arrangement for such devices.

Discharge tubes of which the anode dissipation exceeds a determined value are required to be cooled. It is known to utilize a gaseous cooling medium for this purpose. With suitable proportioning and efficacious construction it is then possible to ensure cooling factors which are higher than those which would be possible with the use of, for example, water.

It is also known to use the casing of the cooler as a support for the discharge tube so that the support for the casing of the cooler also carries the discharge tube. In such cases a compact assembly may be obtained. In the case of air-cooling the cooling air is led into the casing of the cooler by means of channels provided in the side-wall thereof. This may involve difficulties, however. If, as is common practice, the casing of the cooler serves as a support for the discharge tube, the casing will preferably be positioned, for example, on a floor, the inlet and outlet channels for the cooling medium in this case being provided above the floor and occupying space which, in view of the electrical requirements of the equipment, could be used to better advantage. If the support for the casing of the cooler is positioned above the floor, the channels are also located at a determined altitude above the floor and occupy space which could be better used by the parts used in connection with the discharge tube.

All the said disadvantages are obviated by the present invention, according to which in the case of a discharge tube cooled by a gaseous medium and having a cooler which also serves as a support for the discharge tube to be cooled, the cooler is constructed in such manner that the inlet and outlet apertures for the gaseous medium are provided at the bottom of the cooler.

The invention will now be explained more fully by reference to the accompanying drawing showing, by way of example, one embodiment thereof.

A discharge tube, for example a transmitter tube, comprises a glass portion 1 and a metallic anode 2, which is required to be cooled by a gaseous medium, for example air. The anode 2 is surrounded by rings 3 provided for leading the cooling air. The tube comprises a carrier plate 4 which bears on the casing 5 of the cooler so that the latter supports the discharge tube. The casing 5 is constituted by two parts, an upper casing 6 and a lower casing 7, which are joined

2

by means of bolts. As has already been suggested, the lower casing 7 is preferably manufactured from insulating material, for example ceramic material. The bottom of the lower casing 7 exhibits two apertures 8 and 9 through which the cooling gaseous medium is led in and out respectively. The lower casing 7 furthermore comprises a flange 10.

The whole of the combination discharge tube and cooler bears on a support, for example a floor 11. Two holes 12 and 13 provided in the floor correspond to the apertures 8 and 9 provided in the casing of the cooler. Two tubes 14 and 15 lead to the holes 12 and 13 and serve to supply and carry off the cooling gaseous medium respectively. If desired, tube 15 may be dispensed with, if the medium is supplied through tube 14. If the medium is sucked through the installation, then tube 14 may be dispensed with.

It is evident that it is thus possible to obtain a compact, simple solution whereby the transmitter tube and the cooler are accessible on all sides and the space about the tube may be used for positioning any auxiliary parts required, such as coils, condensers, etc. The arrangement according to the invention affords certain advantages also in electrical respect on account of low mutual capacities, and the like.

It is possible for the housing of the device supplying the required gaseous medium under pressure to the cooler and carrying it off at underpressure, to be secured directly to the floor 11, so that the tubes 14 and 15 may be dispensed with and the device becomes even simpler and less expensive of construction.

What I claim is:

1. A cooling arrangement for a discharge tube of the type providing a gaseous coolant for said discharge tube and means of support for said tube, said cooling arrangement comprising a casing having an upper portion and a lower portion of substantially equal volumes, said upper portion being adapted to receive the part of the tube to be cooled, said lower portion being free of said tube and having first and second chambers respectively connected with said upper portion by first and second apertures in said portions, and a bottom portion on said lower portion of said casing, said bottom portion having first and second openings to communicate with said first and second chambers and apertures respectively, for the inlet and the outlet of said coolant.
2. A cooling arrangement for a discharge tube of the type providing a gaseous coolant for said

discharge tube and means of support for said tube, said cooling arrangement comprising a casing having an upper and a lower compartment of substantially equal volumes, said upper compartment being adapted to support said tube and to receive the part of the tube to be cooled, said lower compartment having first and second chambers respectively connected with said upper portion by first and second apertures in said compartments, a bottom portion on said lower compartment and a support for said casing, said bottom portion and said support having first and second registering openings to communicate with said first and second chambers and apertures respectively for the inlet and outlet of said coolant.

3. A cooling arrangement for a discharge tube of the type providing a gaseous coolant for said discharge tube and means of support for said tube, said cooling arrangement comprising a casing having an upper portion and a lower portion of substantially equal volumes, said upper portion being adapted to support the tube, part of said tube including the electrical connections being disposed outside of said casing, and the

part of the tube to be cooled being arranged within said upper portion, the lower portion being free of said tube and having first and second chambers respectively connected with said upper portion by first and second apertures in said portions, a bottom portion on said lower portion and a support for said casing, said bottom portion and said support having first and second registering openings to communicate with said first and second chambers and apertures respectively for the inlet and the outlet of said coolant.
